UNITED STATES PATENT OFFICE

124,358

DESIGN FOR A TEXTILE FABRIC

Abraham L. Oltarsh, New York, N. Y.

Application November 7, 1940, Serial No. 96,387

Term of patent 3½ years

To all whom it may concern:

Be it known that I, Abraham L. Oltarsh, a citizen of the United States of America, residing in New York city, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The dot-and-dash lines on the drawing show the design unit, which unit is repeated in staggered relation, as indicated by the angles A and A'.

I claim:

The ornamental design for a textile fabric, substantially as shown and described.

ABRAHAM L. OLTARSH.
